UNITED STATES PATENT OFFICE.

GEORGE H. FORSYTH, OF CHICAGO, ILLINOIS.

DISK STEEL WHEEL.

1,373,184.

Specification of Letters Patent. Patented Mar. 29, 1921.

Application filed November 26, 1918. Serial No. 264,253.

To all whom it may concern:

Be it known that I, GEORGE H. FORSYTH, a citizen of the United States, residing at Chicago, in the county of Cook and State 5 of Illinois, have invented certain new and useful Improvements in Disk Steel Wheels, of which the following is a specification.

By reason of the growing scarcity of materials suitable for employment in the 10 making of wood wheels and the rapid deterioration of same under stress of weather and liability to damage by rough usage, they are coming into disfavor; the wire wheel has many objectionable features inherent 15 in its manufacture and employment; the steel wheel of spoke or "artillery" type, while desirable from many points of view, is very expensive to manufacture; while the current types of steel disk wheels, if sufficiently strong, are heavy, unsightly, and lacking in resiliency or springiness by reason of the failure to utilize the metal to the best advantage for spring resistance to 20 radial and lateral stresses.

25 The steel disk wheel is recognized as the type most cheaply constructed but it has not met with favor for other than heavy work, such as on trucks and the like, being undesirable on pleasure cars for the 30 reasons briefly indicated above. These wheels have, in general, embodied two disks spaced apart more widely at the center and approaching each other peripherally near the point of attachment to the rim. This 35 emphasizes optically the impression of heaviness and also sacrifices resiliency to strength, while, at the same time, failing to impart strength in the highest degree except as measured by capacity to carry dead 40 load as distinguished from resistance to laterally applied stresses resulting from skidding, striking of curbs, etc. Where single disks have been employed, they too usually have been open to the same objections.

45 The primary object of the present invention is to so re-design the steel disk wheel as to retain or even to reduce its recognized low cost of production; to increase its actual strength under stresses of use while reducing the actual weight; and at the same time imparting an appearance of lightness and symmetry compatible with the best appearing pleasure car.

In order that the invention in its various 55 aspects may be readily understood and appreciated by those skilled in the art, several

embodiments of the invention are set forth hereinafter by way of description and exemplified in the accompanying drawings. It will be readily appreciated, however, that 60 the description and drawings are illustrative only and are not to be taken in an unnecessarily limiting sense. In the drawings—

Figure 1 is a front view of a disk wheel 65 embodying the invention, having a portion of the disk broken away to illustrate the driving connection therewith of the rim and the mounting of the valve stem:

Fig. 2 is a vertical section on the line 2—2 70 of Fig. 1;

Fig. 3 is a similar section showing a modification;

Fig. 4 is a fragmentary section of an 75 adaptation to the clincher type of tire;

Fig. 5 is a fragmentary sectional detail showing a construction similar to that in Fig. 2 with the exception that the rim-retaining bolts are countersunk;

Figs. 6 and 7 are sectional views showing 80 other slight modifications of wheels of the single disk type;

Fig. 8 is a vertical section through a rim 85 embodying the invention and comprising double disks;

Fig. 9 is a fragmentary detail section through the peripheral portion of the wheel illustrated in Fig. 8 but at a different point;

Fig. 10 is a sectional detail showing the disposition of the disks adjacent the hub 90 portion;

Fig. 11 is a fragmentary detail in section illustrating the mounting of the valve stem;

Fig. 12 is a front elevation of that form of 95 wheel illustrated in section in Fig. 13;

Fig. 13 is a vertical section taken on the line 13—13 of Fig. 12;

Fig. 14 is a vertical section illustrating a type of wheel embodying the invention in which two removable rim-retaining rings 100 are employed;

Fig. 15 illustrates an adaptation of the form of construction shown in Fig. 14 to a clincher tire;

Fig. 16 is a detail sectional view taken 10 through the peripheral portion of the wheel represented in Fig. 14 but at a different point;

Fig. 17 is a vertical section through a wheel having a felly portion formed independently of the disk portion; and 110

Fig. 18 is a similar section through a

wheel embodying the independently formed felly portion in connection with disk portions formed of tempered spring steel plane sheet and sprung into position, illustrating 5 also an embodiment of central spacing construction of particular value in this type.

Having reference more particularly, in the first place, to Figs. 1 to 7 inclusive of the drawings, the characteristic feature of 10 the invention will be seen to be the construction of the wheel from a single pressed steel disk so formed as to resist radial strains and stresses on both sides of the plane of the tire, said disk being generally concave as viewed 15 from the front of the wheel, the inner portion of the disk adjacent the hub being shaped for assemblage with and inward radial bearing on the standard hub 21 having front hub plate 22 and rear hub plate developed 20 into the brake drum 23 whereby no special designing of the wheel hub and related parts is necessary. The said disk indicated generally at 24 is shouldered at 25 to bear against the annular wooden insert 26, occupying the space provided for spokes in 25 the standard wood wheel, to which it is secured by bolts 27. The disk is likewise rearwardly supported by the rear hub plate and is preferably shouldered at 28 to form an inner bearing support upon the brake drum 30 23 in the case of those wheels associated with a brake drum; where there is no brake drum this shoulder or bend 28 imparts additional spring or resiliency to the disk between 35 its periphery and hub portion. Beyond the point 28 it bears forwardly to 29 and thence rearwardly and then radially to form a shoulder 30 as a bearing for the rim-retaining ring 31 of ordinary construction 40 removably attached by means of the bolts 32. From the shoulder 30 the disk is again pressed rearwardly transversely or radially as indicated at 34, being marginally beaded as indicated at 35.

45 Thus far, the forms of construction illustrated in Figs. 2 and 3 are substantially identical. Having particular reference now to Figs. 2 and 5, though present in other figures, that portion of the disk 34, is at 50 intervals corresponding to the bolts 32 cupped forwardly to form pockets 36 having their inner walls 37 arranged closely adjacent but spaced from the rim-retaining ring 31 in order to render possible the utilization 55 of short bolts 32. It will be observed that the demountable rim 38 at those portions of the wheel periphery corresponding to the pockets 36 rests adjacent its inner edge, upon the outer walls of said pockets 60 as indicated at 29 most clearly in the lower part of Fig. 2 and in Fig. 5, and in that portion of the wheel periphery intermediate the pockets 36 rests along its inner edge upon the beaded portion 35 of the wall 34; where- 65 as along the medial plane of the wheel, there

is a space between the outer wall of the pockets and the inner face of the rim, which permits a normal amount of yielding of the disk, limited by the eventual abutment of the rim against the outer wall of the pockets whereby to prevent injury to the disk by excessive deformation.

In Fig. 5 of the drawings is illustrated a fragmentary portion of the rim periphery 70 illustrated in Fig. 2, the only difference being that the rim retaining ring 31 is countersunk at the bolt holes as indicated at 31^a 75 in order to bring the nut of the bolt 32 substantially flush with the general plane of the ring.

Having reference now to Fig. 3 of the drawing, the beaded margin 35 of the disk is bent inwardly and instead of serving as a direct support for the demountable rim 38 a ring insert 40 is provided of substantially 80 the same weight metal as the ring 31. This insert is secured to the marginal portion of the disk by riveting or spot welding, serving as an additional reinforcement against 85 stresses and co-operating with the ring 31 for 90 supporting the rim 38. In this form of construction the pockets of Fig. 2 are omitted and a longer bolt 32 is employed for securing the ring 31 in place.

Referring to Fig. 4 of the drawing, we 95 have a form of construction adapted to support a clunker tire, the wall 33 of the disk serving as a shoulder support for the inner flanged members of tire-retaining felly members 41 and 42 which are secured together 100 and to the disk at the wall 34 by means of the bolt 43. The felly members 41 and 42 are countersunk along their medial portions to receive the inlay strip 44 to guard against the inner tube being pinched therebetween.

Referring to Fig. 6, we have the same general construction as is shown in Fig. 2, except that from the disk the shoulder 28 is omitted, the disk having no direct inner bearing upon the brake drum 23 whereby 110 the spring action of the disk is extended from the points 29 to 25. Whether the shoulder 28 be present, as in Fig. 2, or absent, as in Fig. 6, this extending of the spring action throughout the medial portion of the wheel would obtain in the case of such of the car wheels as are not associated with the brake drum. A further point of difference is that the insert 26 is of metal and the pockets 36 are omitted as in the case 115 of Fig. 3 longer bolts 32 being employed in connection with spacing thimbles 45.

In Fig. 7, the ring-retaining bolts 32 are connected directly to the wall 34, pockets being omitted, and outwardly of the wall 34 120 the disk extends rearwardly as indicated at 46 and then at an inclination at 47 and beaded over at 48. Here, as in some of the other forms of construction as for instance in Figs. 2, 3, 5 and 8; that portion of the disk 130

which serves as a support for the inner edge of the demountable rim is of slightly greater normal diameter than the inner diameter of the rim 38 or the ring 40 of Fig. 3, in order 5 that the mounting of the rim or ring will tend to spring the marginal portion of the disk inwardly placing it under spring stress, thus bringing about added resiliency of the wheel when assembled with the rim.

10 Furthermore, this design of wheel compensates for irregularities in rim diameter, utilizing the spring of the disk under the inwardly wedging action of the retaining ring 31 to secure a close fit of the stressed disk 15 within the rim, and also the inner diameter of the comparatively unyielding rim 38 or ring 40 serves to true any peripheral irregularities of the disk. This compensating and truing capacity of the wheel design, is 20 largely contributed to by the fact that the rim retaining ring or wedge members 31 have a reserve degree of lateral movement instead of abutting directly against a portion of the disk, and the opposed surfaces of 25 the rim and disk peripheral portion are spaced apart or disposed at a slight inclination to each other.

It will be observed that the movement inwardly of the ring 31 imparts a resilient outward thrust to the outer edge of the rim at 30 the same time that the horizontal movement given by it to the rim reacts with the resiliency of the disk periphery to impart an outward thrust to the inner edge of the rim. 35 Thus far we have been dealing with wheels made of a single disk. Disks of the general characteristics heretofore pointed out are also peculiarly adapted for use assembled conjointly with a second disk as an added 40 reinforcement where extraordinary strains and stresses are to be anticipated, the second disk coöperating with and supplementing the first. In Fig. 8 of the drawing is illustrated a wheel, one disk and associated parts 45 of which correspond to that illustrated in Fig. 7 and previously described. In addition to the first disk 24, however, a second disk 49 is employed having a shouldered portion 50 for bearing upon the brake drum 23 after 50 the manner of the shoulder 28 of Figs. 2 and 3. The disk 49 bears forwardly in substantially parallel spaced relation to the disk 24 and adjacent the periphery lies against the wall 34 of the first disk, being advanta- 55 geously secured thereto as by spot-welding or riveting, thus affording a double wall as an anchorage for the bolts 32. The disk 49 then bears rearwardly beneath and in contact with the portion 45 of the first disk as 60 indicated at 51, the margin of the second disk being received within the beaded portion 48 of the first disk. This juxtaposed relation of the second disk and the wall 34 and the wall 45 applies only to the walls of the 65 pockets formed by cupping at points corre-

sponding to the locations of the bolts 32 for the purpose of reinforcing said walls at that point. Throughout the intermediate portion of the wheel periphery the second disk 49 extends from the shoulder 50 in a substantially 70 radial direction as indicated at 52 toward its margin where it enters within the lipped portion 48 of the first disk as previously described. This is more clearly shown in Fig. 9 which is a fragmentary vertical section taken 75 at a point in the periphery of the wheel intermediate the cupped portions 53. The pockets 53 of this form of construction furnish a convenient housing for the valve stem 54.

Fig. 10 illustrates a forwardly extending shoulder 55 on the disk 24 bearing on the hub plate 22 to assist in supporting inward thrust and to protect the joint around the outer edge of the hub plate 22 against the 85 admission of water or the like.

Fig. 11 shows a particular configuration of the pocket portions of the second disk 49 to accommodate the valve stem 54 and also shows the marginal deflection of the disk 24 90 outwardly instead of inwardly beneath the demountable rim 38.

In Figs. 12 and 13 are shown in front elevation and in vertical section a wheel wherein the first disk 24 is formed throughout in 95 substantially the same manner as that shown in Fig. 11. In this case, however, the bottom wall 56 of the pockets 57 extends in a substantially radial direction, the disk 49 having its marginal portion beaded over as 100 indicated at 35. As in Fig. 8, the bottom of the pockets are spot-welded to the first disk adjacent the opening for the bolts 32. If desired the disks 24 and 49 may be joined as by welding at 24^a.

Fig. 14 shows a form of double-disk wheel adapted to the employment of two rim-retaining rings 31 arranged on opposite sides of the wheel to bear against the opposite edges of the demountable rim 38. Here the 110 first disk 24 has the same configuration as the corresponding disk in Fig. 13 while the peripheral portion of the disk 49 is of similar configuration to the disk 24, these disks extending in juxtaposed relation and apertured to receive the bolts 32 the opposite headed ends of which engage the two rim-retaining rings 31 and the outer marginal portions of both the disks being bent over in opposite directions to underlie the rim 38. 120 At one point adjacent the valve stem the wall 49 is cupped forwardly to form a pocket giving access to the valve stem as indicated at 58. If desired the disks 24 and 49 may be joined as by spot-welding at 24^a; and instead of the wood filler heretofore shown at the hub a circular metal channel support 49^a 125 may be employed.

In Fig. 15, the demountable rim 38 is omitted and the rim-retaining ring 31 sub- 130

stituted by similar members 59 having their upper edges inturned to a greater extent to act as tire-retaining flanges. In this form of construction the marginal portions of the 5 two disks 24 and 49 are countersunk or channeled to receive the inlay strip 44. This same form of construction at a different portion of the tire periphery, that is to say intermediate the bolts 32, is illustrated in 10 Fig. 16, juxtaposed portions of the two disks being connected fixedly together by the rivets 60. In Figs. 13 and 14 the outwardly turned peripheral edge or edges supporting the rim are preferably slightly upwardly formed whereby after the rim has 15 been placed in position there is introduced between the latter and the said peripheral edge or edges a spring engagement.

In Figs. 17 and 18, in addition to the two 20 disks employed, entirely independent in their relation to each other, is illustrated a supplemental felly member of heavier metal, serving to connect the marginal portions of the two disks and to support the rim. The 25 felly member is indicated at 61. It has a configuration characterized by marginal beads 62 and 63 for taking over the marginal portions of the two disks 64 and 65. It provides a shoulder for the bearing of 30 the rim-retaining ring 31 and also for the rear edge of the rim 38. By its use, it is rendered possible to use disks 64 and 65 of lighter metal than would otherwise be permissible.

35 The two disks 64 and 65 of Fig. 17 are in their medial portion of substantially the same configuration as those shown in others of the views as, for instance, Fig. 8.

Having particular reference, however, to 40 Fig. 18, a form of disk is employed both in front and to the rear which, associated and united by means of this felly member, enables the employment of highly tempered spring steel disks, whereby exceptional 45 strength is obtained accompanied with great resiliency.

The forward disk 66 and the rear disk 67 are of slightly different diameter but otherwise the same. They are punched 50 from a plane sheet of tempered steel and are not formed in dished shape by a press, which would be impracticable. The felly member 61 having been formed by rolling of relatively heavy metal, the disk 66 and the 55 disk 67 are placed on opposite sides thereof and forced inwardly toward each other at their central portions whereby they are sprung into cup shape and their marginal portions, originally held apart by the beaded 60 margins 62 and 63 of the felly member, are contracted so as to clear the beads and snap into the space formed thereby. They are then permitted to separate sufficiently in 65 their central portion to allow their margins to be forced outwardly under the spring of

the disks as far as permitted by the felly member, by which they are held under inwardly applied radial stress. Here they are retained by the inherent tension of the metal tending to resume its former plane. 70 This forms a wheel of exceeding strength and resiliency, presenting a maximum of resistance to deforming strain and insuring a return of the wheel to its original shape after deformation. 75

As a particularly efficient method of assembling the disks and felly member in the relation above described, and holding the same in assembled relation, I arrange within in the space between the two disks about the 80 hub portion two telescopically disposed cup-like plates 68 and 69, the inner wall of one and the outer wall of the other being threaded for mutual interengagement as shown. The inner peripheries of these two 85 plates are provided with notches or holes 70 for engagement by a spanner wrench or the like in order that they may be angularly adjusted relatively to each other. By turning these plates in one direction they are 90 caused to approach one another and thus allow the central portion of the disks to be pressed together dishing the disks and reducing their diameter sufficiently to allow them to enter the beads 62 and 63 of the 95 felly member. Having done so, they are turned in the opposite direction, spacing the central portion of the disks farther apart and thus supplementing the spring tension of the disks in firmly seating the margins of 100 the same within the beads of the felly member. Hereafter the plates 68, 69 constitute a filler member holding the plates in fixed relation at their centers and being themselves prevented from further relative 105 movement by means of the bolts 27 uniting the hub plates 22 with the brake drum 23 and transfixing the filler plates 68 and 69, which latter prevent any relaxing of the 110 spring stress of the disks due to the tightening of the bolts 27. Herein the valve stem 54 is made exteriorly accessible by passing through the disk 67, and the ring-retaining bolts 32 have their heads 32a disposed within in the space between the disk 67 and the 115 felly member 61, being prevented from turning in the felly member by the engagement therewith of a polygonal shank.

An interlocking driving connection between the felly member or portion of the 120 disk and the rim may be provided by forming depressions or elevations 71 on the former for engagement with the driving lug 72 of the rim, as indicated, for example in Figs. 2 and 9. Obviously, instead of specially provided elevations or depressions 71, the same interlocking relation to the driving lug may be had by disposing the lug in the circumferential space between the outer walls of two adjacent pockets 36. Interme- 125 130

diate the pockets, also, the space between the disk portion 33 and the rim provides for the accommodation of the latching device of the two ends of the usual demountable 5 rim.

I claim:

1. In a wheel, the combination with the hub and rim, of a pressed sheet steel disk having its inner portion secured to and bearing radially upon the hub, its medial portion forwardly concave, and its outer portion reversely bent to form a felly, the margin of the disk arranged at an inclination to form a rear rim-retaining bead, and a rim-retaining ring adjustably attached to the forward peripheral disk portion opposite its beaded margin.
2. In a wheel, the combination with the hub and rim, of a single sheet metal disk having its inner portion secured to and bearing radially upon the hub, its medial portion forwardly concave, and its outer portion reversely bent to form a felly adapted to support a demountable rim, that portion 25 of the disk adjacent the hub and felly being in front of and the intermediate portion in the rear of the median plane of the wheel, and releasable means for holding the rim on the felly.
3. In a wheel, the combination of a hub portion, a disk body having a peripheral overhanging felly portion terminating in an elevated marginal rim-supporting bead, the felly provided in its medial portion with 35 spaced projections extending radially slightly less than the height of the bead whereby to form a reserve rim support as the bead yields under abnormal shock.
4. In a wheel, the combination of a hub portion, and a disk body having a peripheral overhanging felly portion terminating in an elevated marginal rim-supporting bead, the felly cupped at intervals in the medial portion thereof to provide portions projecting 45 radially slightly less than the height of the bead, whereby to form a reserve rim support as the bead yields under abnormal shock.
5. In a steel disk wheel for demountable rims, the combination of a disk body portion, and a rim carrying portion, the latter provided on its periphery with a series of separated rim supporting elevations arranged to provide therebetween in the medial plane of the wheel a clearance space for 55 the accommodation of the usual driving lug and latch mechanism of a demountable rim.
6. In a wheel, the combination with the hub and rim, of a sheet steel disk having its inner portion secured to the hub, its medial portion forwardly concave, and its outer portion reversely bent to form a felly, the margin of the disk arranged at an inclination to form a rear rim-retaining and supporting bead, said felly portion provided at intervals 65 inwardly of the bead with forwardly

cupped pockets, a rim-retaining beaded ring disposed on the forward side of the felly opposite its beaded margin, and ring securing bolts seated in the pockets.

7. In a wheel, the combination of a hub, 70 and a disk body peripherally offset to provide a felly for receiving a demountable rim, the felly provided on its periphery with portions spaced unequally from the inner face of the rim, the most closely adjacent of the 75 portions serving as a rim support and the space separating the rim from the other of the portions serving to accommodate the usual rim latch.

8. In a wheel, the combination with the 80 hub and rim, of a pressed sheet steel disk having its inner portion secured to and bearing radially upon the hub, its medial portion forwardly concave, and its outer portion reversely bent to form a felly, the margin of the disk arranged at an inclination to form a rim-retaining bead, and a rim-retaining ring removably attached to the forward peripheral disk portion opposite its beaded margin, the disk having pockets formed 85 therein adjacent the felly, the outer extremities of the pockets terminating radially a slight distance short of a rim mounted on the felly whereby to form an abutment to oppose undue yielding of the felly under radial 90 stresses.

9. In a wheel, the combination with the hub and rim, of a pressed sheet steel disk having its inner portion secured to the hub, its medial portion forwardly concave, and its 100 outer portion reversely bent to form a felly, the margin of the disk arranged at an inclination to form a rear rim-retaining bead, the felly portion of the disk extending transversely of the wheel toward the rear and 105 then radially and terminating marginally in an inclined rim-retaining bead, said felly portion provided at intervals inwardly of the bead with forwardly cupped pockets, a rim-retaining beaded ring disposed on the 110 forward side of the felly opposite its beaded margin, and ring securing bolts seated in the pockets, the outer extremities of the pockets terminating radially a slight distance within a rim mounted on the felly, whereby to form 115 a reinforcing abutment to oppose undue yielding of the felly under radial stresses.

10. In a wheel, the combination with a hub portion, of a disk centrally secured thereto with its peripheral portion laterally bent and extending across the plane of impact to form a felly with a rear marginal bead, the felly portion provided at intervals with inwardly concave pockets, a rim supported by its rear edge of the bead of the 120 felly, and a rim-retaining ring fulcrumed with its inner edge on the disk and with its outer edge supporting the forward edge of the rim.

11. In a wheel, the combination with a 130

6
hub portion, of a disk centrally secured thereto with its peripheral portion laterally bent and extending across the plane of impact to form a felly with a rear marginal bead, the felly provided at intervals with inwardly concave pockets having outwardly convex walls extending slightly above the general medial surface of the felly, a rim supported by its rear edge on the felly bead, 5 and a rim-retaining ring fulcrumed with its inner edge on the disk and with its outer edge supporting the forward edge of the rim.

12. In a wheel, the combination with a hub 15 portion, of a disk centrally secured thereto with its peripheral portion laterally bent at an inclination to form a felly with a rear marginal bead, the felly provided at intervals with inwardly concave pockets having

outer walls projecting beyond the general 20 surface of the felly and merging rearwardly into the bead below the extreme elevation thereof, the rim supported by its rear edge on the edge of the felly bead closely adjacent the outer walls of the 25 pockets, and a rim-retaining ring fulcrumed with its inner edge on the disk and with its outer edge supporting the forward edge of the rim, whereby the outer walls of the pockets form a reserve support for the 30 rim under abnormal shock.

In testimony whereof I have hereunto signed my name in the presence of two subscribing witnesses.

GEORGE H. FORSYTH.
